UNITED STATES PATENT OFFICE.

ERASMIUS M. DEANE, OF ST. PAUL, MINNESOTA.

GRAIN-BINDER.

SPECIFICATION forming part of Letters Patent No. 291,497, dated January 8, 1884.

Application filed March 24, 1883. (No model.)

To all whom it may concern:

Be it known that I, ERASMIUS MILLER DEANE, a citizen of the United States, residing at St. Paul, county of Ramsey, State of Minnesota, have invented certain new and useful Improvements in Grain-Binders, of which the following is hereby declared to be a full, clear, and exact description.

The invention relates to that class of automatic binders wherein the binding mechanism proper is tripped or brought into action through the medium of the accumulating gavel; and it consists of certain improvements in the construction of a machine for effecting this result, as hereinafter described, and distinctly defined in the claims following.

In the accompanying drawings, Figure 1 is a top plan view, Fig. 2 a side elevation, and Fig. 3 a sectional view on line $x-x$, Fig. 1, of one form of machine embodying the improvements, only so much of the complete grain-binder being shown as is necessary to a clear understanding of the invention. Figs. 4, 5, 6, and 7 are minor detail views. Fig. 8 is a sectional view, similar to Fig. 3, of a modified form of machine; and Fig. 9, a detail view of a sliding box for the packer-shaft thereof.

For convenience, the invention will be fully shown and described as applied to the well-known Appleby grain-binder, set forth in Letters Patent No. 212,420, February 18, 1879, and No. 260,634, July 4, 1882, respectively. It is to be understood, however, that the invention is by no means restricted in usefulness to that particular type of machine, but may be applied to other forms as well, and whether these employ cord or wire in securing the gavel.

The binder-frame A is sustained at the side of the main harvester-frame by the tubes or rods c^2 in manner well understood. Across the binder-frame and beneath the binder-table extends the drive-shaft M, having near its outer end the sprocket-wheel b, which, through a sprocket-chain engaging therewith, and with a like wheel on a driving-shaft of the harvester, communicates the power necessary to operate the several moving parts of the binder. The shaft M is sustained by the frame A within any of the ordinary journal boxes or bearings, and at its inner end is secured, by suitable uni-

versal coupling-joints, F F, to the inner end of packer-shaft M', which is sustained by the swinging shaft-supports c c, the projecting journals c' of which are seated overhead in boxes d d, bolted to the binder-frame. By using the universal couplings or like connections between the main drive-shaft and packer-shaft M', the latter, being sustained by swinging supports c c, is free to move bodily to and fro without binding or risk of disengagement or disarrangement of the shaft carrying the sprocket-wheel b. Two cranks, N N, set opposite each other on the shaft M', carry the packers L L, the lower ends of which are joined to the links n, pivoted to the binder-frame. The binder-arm K, mounted on shaft o, swings up through the binder-table, between the packers L L, and free from interference with packer-shaft M'. 70

At the back of the shaft-supports c c are projecting lugs or ears c', adapted to receive between them the reduced end of the base or seat k' of a spindle, k, which is pivoted thereto. The spindle k at its opposite end passes through a perforation in the stop-plate i, secured to the binder-frame, and carries a threaded nut, by means of which the tension of spring h, encompassing spindle k, and bearing at its ends against seat k' and stop-plate i, respectively, may be regulated. The pivotal connection between spindles k k and supports c c allows these latter, together with packer-shaft M', which they sustain, to swing backward about journals c', and against the tension of springs h, without undue stress or strain. A trip-rod, l, keyed at one end within a perforation of one of the journals c' of swinging supports c, so as to rotate therewith, is sustained near its opposite end in the side frame 90 of the binder, and has secured to it a trip-crank, m, which bears against a secondary trip-lever, o', (or an adjustable nut thereon,) mounted upon a stud or arbor, r, at the side of the binder-frame. The secondary trip-lever o' rests at its end beneath the primary trip-lever Q, journaled upon shaft o of the binder-arm, said primary lever, as well understood, bearing against the long arm of a lever-stop, P, pivoted to the side of a drive-pinion, s, 100 which is journaled loosely upon drive-shaft M. An arm, O, fastened rigidly to shaft M,

and having the projecting pins or catches *t*, revolves constantly with said shaft, and imparts motion to pinion *s* whenever primary lever *Q* rises free and away from the long arm 5 of lever-stop *P*, so that the short arm thereof may be forced upward by a suitable spring, *v*, into the path of the pins *t*, thus dogging or locking the pinion *s* to revolving shaft *M*. The pinion *s* communicates its movement 10 through intermediate gear-wheels to the drive-wheel *E*, which controls the operation of the binding mechanism, the binder-arm, and the ejectors; but as these several parts, their relation, and coaction form no part of this invention, and, besides, for the Appleby type of machine are well understood, and can be readily traced therein from the outline already given, a further detailed description thereof is not deemed requisite.

20 The crank-arm *p*, keyed to the shaft *o*, of the binder-arm, carries pivoted thereto a short rod encircled by spring *y*, the tension whereof may be adjusted by suitable thumb-nut, so that the force necessary to lift primary trip-lever *Q*, against which lever the spring *y* bears, 25 may be varied at will, and for a purpose presently to be described.

When loose grain is falling upon the binder-table from the elevator-apron, the continuous 30 revolution of drive-shaft *M* causes the packers *L* on cranks *N* to rise alternately through slots in the table, advancing the loose grain, and compacting the same against the gavel-supporting finger *S*, (see Fig. 8,) or against any 35 other suitable stop which may be arranged to arrest the passage of the grain preliminary to applying the band to the gavel. As the loose grain accumulates it offers more and more resistance to the alternating action of the packers *L*, which resistance, being reflected upon shaft *M'*, to which the packers are secured, causes said shaft to swing gradually backward about its pendent supports *c* and against the tension of springs *h* on the spindles *k*. The 40 movement of swinging support *c* causes trip-rod *l*, keyed to journal *c'* of said support, to rotate slightly, thereby raising trip-crank *m* against the secondary trip-lever *o'*, which in turn lifts primary trip-lever *Q* away from the 45 lever-stop *P*. Spring *v* thereupon forces the short arm of lever-stop *P* into the path of pins *t*, so that pinion *s* is locked with constantly-revolving arm *O* of the shaft *M*, and the drive-wheel *E*, through intermediate gear-wheels, is 50 made to describe one complete revolution to operate the binder and compressor arms, the binding mechanism, and the ejectors, as well understood. The binder-arm, in rising above the 55 table to apply the band, advances the gavel and compresses the same somewhat, so that the packers, being relieved from the resistance of the gavel, are free to return, together with packer-shaft *M'*, to their normal position, the springs *h* acting against the swinging supports *c* to accomplish this end. The reverse 60 movement of supports *c* causes a correspond-

ing reverse rotation of rod *l*, and through it a reversal or return to first position of the trip-crank *m* and secondary trip-lever *o'*. The primary trip-lever *Q* and lever-stop *P* return 70 to position when binder-arm passes below the table. The pinion *s* is thereby put out of clutch with arm *O*, so that said pinion, and with it the drive-wheel *E*, is brought to rest, and remains thus, pending the accumulation of 75 grain sufficient for another gavel.

It is obvious that the tension of springs *h* may be adjusted by the set-nuts, so as to offer greater or less resistance to the backward movement of swinging supports *c* and shaft *M'*, and that thereby and in like degree will the size and compactness of the gavel be determined, said springs acting in conjunction with the spring *y* to that end, and to control the action of the trip.

If desired, the springs *h* may be omitted, in which event the tension of spring *y* against primary trip-lever *Q* will govern the movement of trip-rod *l*, supports *c*, and shaft *M'*; or, on the other hand, the spring *y* may be discarded and springs *h* alone be employed, though in general it is preferred to use both in regulating the density of the gavel. Again, the main drive-shaft *M* may be connected to packer-shaft *M'* by other means than the couplings *F*. These and all like modifications within the skill of the mechanic to accomplish involve no essential difference in invention, and can be readily effected, as convenience may suggest or the peculiarities of the machine may require, without in any wise departing from the spirit of the invention.

As thus far detailed, the operation of the improved automatic tripping mechanism is shown to be dependent directly upon the impact of the packers against the accumulated grain and the reaction or resistance arising therefrom, which is reflected upon the movable shaft of said packers. In the Appleby patents, heretofore referred to, the gavel rests 105 against a certain supporting-finger, *S*, which, through the stress of the gavel thereon, finally rocks a shaft, 2, an outer arm, 3, of which raises the trip-lever *Q* away from the lever-stop *P*. This trip mechanism of the Appleby binder 110 may be retained entire and caused to co-operate with that which has been heretofore set forth, without further change whatever, in which case it is plain that both gavel-support *S* and packers *L* are sensitively set and coact, 115 as against the pressure of the grain, to automatically dog the pinion by which the binding mechanism proper is intermittently brought into play. To more certainly effect this co-operation of the several parts, to simplify construction, and to enable the invention to be easily adapted to the Appleby machines now in use is the object of the style of machine illustrated by Figs. 8, 9, and 10. As shown therein the extension *z* of the gavel-supporting finger *S* is formed with an eye to receive the reduced shank of an arm, *R*, con-

5 neeted to a rock-shaft, 2, said shaft being sus-
tained in suitable bearings of the binder-frame,
and having at its outer end an arm, 3, which
rests against the under side of the primary
trip lever or arm Q.

10 So far the construction is the same as is set
forth in the aforementioned Letters Patent,
which is equally true of the construction of lever-stop P, pinion s, and arm O, having catches
15 t thereon, these latter-named parts being, more-
over, already described in the present specifi-
cation. It is deemed unnecessary, therefore,
to make any further description in detail of
them or of their mode of operation.

15 Through a perforated lug, o³, projecting
from rock-shaft 2, passes a connecting-rod, o⁴,
having a threaded nut thereon, and pivotally joined
20 at its opposite end to an ear of one of
the sliding boxes c⁴, which sustain the shaft
M' of the packers L. The sliding boxes c⁴ are
25 in this form employed in lieu of the swinging
supports c, to allow for the to-and-fro play of
packer-shaft M', as against the impact of the
accumulated grain, although, as will presently
30 appear, the swinging supports c may be used
with equal success. The boxes c⁴ are retained
in place on binder-frame A by headed bolts c⁶,
passing through slots in the boxes, there be-
35 ing thimbles c⁷ on the bolt-shanks, to allow of
more easy movement of the boxes. The spin-
dles k, pivoted to boxes c⁴, the stop-plates i,
and springs h are the same in relation and op-
eration as heretofore detailed. In this form
40 of machine it is plain that as the grain accu-
mulates against the gavel-supporting finger S,
the packers L, and with them their shaft M',
are gradually forced backward, the shaft mov-
ing with sliding boxes c⁴, and these latter
45 against the tension of springs h. Connecting-
rod o⁴ thereupon coacts with the pivoted fin-
gers S to rock the shaft 2 far enough to re-
lease the dog which controls the movement of
the binding mechanism, as well understood.
50 This direct co-operation of yielding gavel-sup-
porting fingers with yielding packers to rock
the same shaft, has the merit of simplicity and
sensitiveness, so that by adjustment of spring
y and of springs h, (where these latter are
55 used,) the tripping action can be effected with-
out undue strain and the density of the gavel
and the uniformity thereof more certainly in-
sured.

Instead of rotating a rock-shaft, it is obvious
55 that the yielding packers, as mounted, may be
made to operate a trip-lever where such is em-
ployed, to control the binder-clutch, and that
either the swinging supports c or sliding boxes
c⁴ may be used to sustain the packer-shaft M',
as convenience may suggest. Again, the yield-
60 ing packer-shaft and its connections, as here-
in described, may be used exclusively to trip
the binding mechanism, in which event the
sensitively-set gavel-supports, or other like
expedients to actuate the rocking shaft 2, will
65 be entirely dispensed with.

Without limiting myself, therefore, to the

precise details herein set forth, and again de-
claring that the improvements are not re-
stricted to any one special form of grain-binder,

70 What I claim as new, and desire to secure by Letters Patent, is—

1. In a grain-binder, the combination, with
the adjustably-yielding packer-shaft, of the
adjustably-yielding trip-lever which controls
75 the binder-clutch, said parts being so arranged
that the movement of the packer-shaft shall
be communicated to the trip-lever, substan-
tially as described.

2. In a grain-binder, the combination, with
the yielding packer-shaft, of the adjustable
80 spring mechanism for controlling the move-
ment of said shaft, substantially as described.

3. The combination, with the main drive-
shaft and with the yielding packer-shaft con-
nected to the inner end thereof, and sustained
85 in movable bearings, of the trip mechanism
which controls the binder-clutch, substantially
as described.

4. The combination, with the main drive-
shaft and with the revolving arm thereon hav-
ing catches to engage the binder-pinion, of the
90 movable packer-shaft connected to the inner
end of said main shaft, and the trip-lever which
controls the binder-clutch, substantially as de-
scribed.

5. In a grain-binder, the combination, with
the packers mounted upon cranks and adapt-
ed to work through the binder-table, of the
95 movable packer-shaft, the spring for control-
ling the movement of said shaft, means for ad-
justing said spring, and suitable means for
communicating the movement of the packer-
shaft to the binder-clutch, substantially as de-
scribed.

6. The combination, with the packer-shaft
100 and its sliding boxes, of the connecting-rod,
the rock-shaft, and the trip-lever that controls
the binder-clutch, substantially as described.

7. The combination, with the trip - lever
110 which controls the binder-clutch, of a mova-
ble packer-shaft and a movable gavel-support,
both arranged to shift by impact of the accu-
mulating gavel, thereby tripping said lever
115 to start the binding mechanism, substantially
as described.

8. A revolving shaft having packers set on
the cranks thereof, in combination with slid-
ing boxes for said shaft, and the trip-lever
120 which controls the binder-clutch, the several
parts being relatively arranged, substantially
as described, so that the impact of the accu-
mulating gavel shall act upon said crank-
shaft, which moves the trip-lever that shifts
125 and starts the binding mechanism, substan-
tially as set forth.

9. A revolving shaft having packers set on
the cranks thereof, in combination with yield-
ing bearings or boxes for said shaft, a mova-
ble gavel-support, and the trip-lever which
130 controls the binder-clutch, the several parts
being relatively arranged, substantially as de-
scribed, so that the impact of the accumulat-

ing gavel shall cause said lever to shift and start the binding mechanism, substantially as set forth.

10. The combination, with the packer-shaft, 5 its yielding supports and adjusting-springs, of the trip-lever to control the binder-clutch, an adjusting-spring for said lever, and suitable mechanism intermediate the supports and lever, whereby, in co-operation, the accumulating gavel will shift the shaft and cause it to act upon the trip-lever, substantially as described.

11. The combination, with the packer-shaft M', mounted in yielding boxes, of the tension-spring h, the connecting-rod o⁴, the rock-shaft 10 15 20 25

2, and the trip-lever Q, controlling the binder-clutch, substantially as described.

12. The combination, with the packer-shaft M', mounted in yielding boxes, of the tension-spring h, the connecting-rod o⁴, the rock-shaft 2, having arm R, the gavel-supporting fingers S, and the trip-lever Q, controlling the binder-clutch, substantially as described.

In testimony whereof I have hereunto set my hand this 13th day of March, A. D. 1883. 25

ERASMUS M. DEANE.

In presence of—

J. H. RANDALL,
CHAS. W. HILL.
